UNITED STATES PATENT OFFICE.

AUGUSTINE J. POCOCK, OF DAYTON, OHIO; ZADIA POCOCK, ADMINISTRATRIX OF SAID AUGUSTINE J. POCOCK DECEASED, ASSIGNOR TO THE DAYTON PUMP & MANUFACTURING COMPANY, OF DAYTON, OHIO, A CORPORATION OF OHIO.

PUMP.

Application filed October 4, 1920. Serial No. 414,467.

To all whom it may concern:

Be it known that AUGUSTINE J. POCOCK, a citizen of the United States, residing at Dayton, in the county of Montgomery and 5 State of Ohio, has invented certain new and useful Improvements in Pumps, of which the following is a specification.

This invention relates to certain improvements in pumps. The objects of the invention are several principally among which is to provide a pump construction and organization that permits of easy access to the valves and pistons whenever necessary and without the necessity of disconnecting either 10 the suction or discharge pipes.

A further object of the invention is to provide a pump which runs smoothly and noiselessly thereby avoiding the usual annoyance common in pumps and which is due 15 to pounding, or hammering as it is more commonly termed.

With these objects in view the improvements relate more specifically to the construction of the water box, and before entering into a detail description thereof it 20 may be well to briefly refer to efforts that have been put forth to avoid the shocks or hammering annoyance so common in pumps as heretofore constructed.

25 Pumps with a single cylinder, whether single acting or double acting, usually produce very much of a shock when passing over centers or rather each time the piston changes direction. This condition is caused

30 by the high speed of the piston in one part of its stroke coming to a stop at the terminal of the stroke either way. This has always been an experienced trouble with a single cylinder pump and attempts have been made

35 to counteract this undesirable feature. The duplex or double cylinder pump does away with it to a certain extent and the three cylinder or triplex pump has been and is still being used for the avoidance of shock. In

40 a word, the water column in the discharge pipe is made to move more steadily, as two or three cylinders are working, inasmuch as only one of the cylinders is passing over the dead center at any time, the shock thereby

45 being minimized.

In the present case the object of the present improved water box is to produce a steadier flow in the water column or discharge, more particularly in a single cylin-

der pump. I do not confine myself however 55 to a single cylinder inasmuch as the same principle applies to multiple cylinder pumps. The main features which are employed to bring the desired results about, are first; a shock chamber around the outside of the piston barrel and above the level 60 of the inlet or suction valves. All the volume of this chamber around the outside of the said barrel or barrels and above the inlet or suction valves, acts as a pulsation chamber, inasmuch as it may be partially filled with air which cannot get out by reason of 65 said valves being low down. Therefore, the air in said chamber will become rarefied or compressed in receiving and steadyng the 70 incoming water through the suction or inlet pipe. It will be noted from the illustrations that from the inlet or suction valves the water is directed by curves in the upper 75 portions of the valve plates which serve to throw it without shock towards the cylinder as the piston moves forward. As it returns, it thrusts the water up the curved top and out through the discharge valve into the air chamber and this valve being barely covered with water and so near, the compressible air in the chamber responds very readily 80 to the action of the piston or plunger on the water, thereby virtually discharging the 85 water into the compressed air in the air chamber, which responds to the rush of water at the high points of the stroke, and then reacts on the water passing into the discharge pipe at the time the piston is on its dead center, thus compressing and expanding 90 the air with each pulsation of the pump, but keeping the pressure steady on the discharge line. In a word, absorbing the differential between the high speed of the piston 95 and the stop at the end of the stroke.

This has been attempted in the various pumps that have air chambers at some point on the discharge line, or even in the discharge chamber. But the utilization of features peculiar to my invention accomplishes 100 what has heretofore failed of accomplishment.

As a result of the construction which achieves the above ends another advantage of great value is the accessibility to parts 105 subject to most wear and whereby a person of little or no mechanical ability may look into possible trouble without disconnecting

pipes or dismantling the pump,—the simple thing to be done being the removal of the valve plates when it will be found that the discharge valve is on the valve plate and 5 readily gotten at, and the suction valve is standing out uncovered by the taking off of said valve plate. By the removal of the end valve plate the piston can be examined and if necessary, very readily taken out of 10 the barrel. An inexperienced operator by taking off what may be termed a nut on the end of the piston, may readily remove with the hands the piston itself with the cup leathers or other packing and follower, 15 and can readily replace the leathers if necessary and screw the completed piston head back on the rod. This is a very material improvement over the common way of removing the nut which holds the cup leathers or 20 packing on the rod, and then having to use a packing hook or some similar instrument to withdraw the leather—usually in specially small work, a very different operation, and then the replacement of the leathers and 25 really building up the piston in the barrel where it cannot be seen or conveniently gotten at.

Preceding a more particularly description of my improvements reference is now 30 made to the accompanying drawings of which Fig. 1 is a horizontal longitudinal section of a pump containing my improvements, the same being on the line 1—1 of Fig. 2. Fig. 2 is a vertical longitudinal section of the pump on the line 2—2 of Fig. 1. Fig. 3 is a cross section of the water box on the line 3—3 of Fig. 1, and Fig. 4 is an end elevation of the water box showing both 35 valve plates and the connections of the inlet or suction and discharge pipes.

In a detail description of the improvements in connection with the accompanying drawings, similar reference characters indicate similar parts as they appear in said 40 drawings.

The pump illustrated in the drawings is of a single cylinder double acting type, as before intimated, but it may be of a single cylinder single acting type, or a multiple 45 cylinder type, either single or double acting, the improvements being applicable to any of these different types with equal facility. The water box is formed or built with the upper portion —1— providing a combined 50 water and air chamber —2— in which the water is discharged, and a lower portion —1'— forming the suction or inlet chamber —8—. Into the chamber —2— the water is discharged alternately through two discharge valves —3— and —3'— in the front 55 and side of the water box respectively. Below the said chamber —2— is the cylinder —5— which may or may not be of a removable type. In this cylinder the piston —6— reciprocates, said cylinder —5— being

forced into its position in the casting and surrounded by space —7—. The space 7 is closed at its top and communicates with the suction chamber at its bottom, thereby permitting air to be trapped therein which provides a shock space on the suction side of the pump. An inlet or suction pipe —9— connects with an inlet opening —10— in the lower side of the water box leading to the suction chamber —8— by means of a union 75 —11—. A discharge or outlet pipe —12— from the pump communicates with the combined water and air chamber —2— through a union —13— which connects it with a discharge nozzle —14— extending down on the 80 interior of said chamber —2— to a point approximately in line with the discharge valves —3— and —3'—. The suction valves —15— and —15'— in the end and side of the water box respectively, control the outlet 85 from the suction chamber —8— and it will be observed these valves lie below the cylinder —5—. The end of the water box has a detachable valve plate —16— held thereon by means of cap screws —17—. The said 90 valve plate provides a chamber —18— into which the water is drawn through suction valve —15— on the back stroke of the piston. The return stroke forces the water through the discharge valve —3— into the water and air chamber —2—. The discharge valve —3— is mounted in the top of the end valve plate —16— and it will be seen that upon detaching said valve plate both valves are 95 readily accessible as well as the piston —6—. The piston consists of a head which screws on to the end of the piston rod —19— and has the appearance of a nut on the end of said piston rod. A follower —20— screws on to the inner end of the piston head —6— and between said head and follower —20— the cup leathers —21— are placed with an intervening washer —22—. Upon the removal of the end valve plate —16— the 100 valves —3— and —15— as well as the piston 105 become readily accessible as before stated and thus the piston head including the leathers and the follower may be readily removed in the hand and the leathers replaced if necessary and the whole returned as a unit. This is an important accomplishment 110 in these pumps when considered from the user's standpoint.

A valve-controlled air inlet pipe —23— is 115 tapped into the upper portion of the end valve plate —16— and provides an air communication with the water and air chamber —2— through valve —3—. The suction and discharge valves —15'— and —3'— respectively, at the side of the water box operate alternately with the suction and inlet valves —15— and —3— at the end as required by the double acting character of the pump. The suction and discharge valves —15'— and —3'— are inclosed by a valve 120

125

130

plate —16'—, the discharge —3'— being mounted therein. The said valve plate —16'— is secured to the side of the water box by cap screws —17— and it provides on 5 the interior thereof a chamber —24— which opens to the inner end of the piston cylinder through a lateral passage —25— in the water box. The water is drawn from the inlet or suction chamber —8— through the suction 10 valve —15'— on the same stroke of the piston that opens discharge valve —3—. From chamber —24— the water is forced by the piston through the discharge valve —3'— into chamber —2— on the same stroke of the 15 piston that opens suction valve —15— as will be readily understood. The piston rod —19— passes through a stuffing box or gland —26— and is connected to the driving crank shaft —27— through a connecting rod 20 —28— and crosshead —30—. The bearings —29— of the crank shaft are in the sides of the crank case and are close to the oil box, the arrangement being close and compact with the result that the strain is entirely central and the pump is enabled to 25 operate smoothly and without noise more efficiently.

Having described my invention, I claim:

1. In a pump, a water box having a combined water and air chamber and a suction chamber, a pump cylinder containing a piston and arranged between said combined water and air chamber and said suction chamber and surrounded by a chamber communicating with said suction chamber and constituting a shock chamber, a discharge valve forming an inlet to the lower portion of said combined water and air chamber, and a suction valve forming an outlet for said suction chamber, a valve plate forming a closure for said valve and the pump cylinder, and a passage from the suction valve to the discharge valve, and an outlet pipe communicating with said combined water and air chamber.

2. In a pump, a water box having an inlet and exhaust, said box being provided with a gland at one end thereof, a cylinder mounted in said box, a piston mounted in said cylinder, a rod extending from said piston and through said gland, a valve plate mounted on the side of said box, another valve plate mounted in the end of said box opposite said gland, said plates forming passageways between the inlet and exhaust and the cylinder, valves mounted in said passageways, whereby access may be had to the valves and cylinder without disturbing the inlet, the exhaust and the gland.

3. In a pump, a water box having an inlet and an exhaust, said box being provided with a gland at one end thereof, a cylinder mounted in said box, a piston rod extending through said gland and into said cylinder, a piston head mounted on said rod and ex-

tending into said cylinder, cup leathers mounted on said head, a follower mounted on said head and adapted to hold said cups on said head, a valve plate mounted on the side of said box, another valve plate mounted on the end of said box opposite said gland, said plates forming passageways between the inlet and exhaust and the cylinder, valves mounted in said passageways, whereby said piston may be removed from the cylinder without disturbing said rod and gland.

4. In a pump, a water box having a combined water and air chamber and a suction chamber, a pump cylinder containing a piston between said combined water and air chamber and suction chamber and surrounded by a chamber communicating with the suction chamber and constituting a shock chamber, a discharge valve forming an inlet to the lower portion of said combined water and air chamber, a suction valve forming an outlet from said suction chamber, a valve plate forming a closure for said valves and the pump cylinder and a passage from the suction valve to the discharge valve, the removal of said plate enabling ready access to said valves and cylinder, and an outlet pipe on the interior of said combined water and air chamber with the receiving end thereof substantially in alignment with the upper plane of the discharge valve.

5. In a pump, a water box having a combined water and air chamber in the upper portion thereof and an inlet or suction chamber in the lower portion thereof, a pump cylinder arranged between said combined water and air chamber and said suction chamber, said cylinder having a space surrounding it communicating with the suction chamber, a suction valve controlling the outlet from said suction chamber, said suction valve and the pump cylinder being exposed at the end of the water box, a valve plate forming a closure for said pump cylinder and suction valve and being detachable from the water box, a discharge valve mounted in said valve plate and controlling the passage from the suction valve to the combined water and air chamber, and a discharge pipe in said chamber extending from a plane approximately coinciding with the upper plane of said discharge valve.

6. In a pump having a single cylinder, a water box having a combined water and air chamber in the upper portion thereof and an outlet or suction chamber in the lower portion thereof, a pump cylinder between said chambers surrounded by a chamber which communicates with the upper portion of the suction chamber and forms a shock chamber, suction valves forming outlets from the lower portion of the suction chamber, said suction valves being below the said shock chambers, discharge valves forming

an inlet to said combined water and air chamber, valve plates forming closures for said suction valves and the pump cylinder and detachably connected with the water box, and discharge valves mounted in said valve plates and controlling the passage from the suction valves to the combined water and air chamber.

7. In a single cylinder pump, a water box having a combined water and air chamber in the upper portion thereof and an inlet or suction chamber in the lower portion thereof, a pump cylinder arranged between said chambers and having a space surrounding it serving as a pulsation or shock chamber, a suction valve below said pulsation chamber and forming an outlet from the inlet or suction chamber, a valve plate forming a detachable closure for said pump cylinder and suction valve, said valve plate forming a water passage at the end of the water box into which an end of said cylinder and the suction valve projects, and a discharge valve mounted in said valve plate and controlling the discharge of water to the combined water and air chamber.

8. In a single cylinder pump, a water box having a combined water and air chamber in the upper portion thereof and an inlet or suction chamber in the lower portion thereof, a pump cylinder arranged between said chambers and having a space surrounding it serving as a shock chamber, a suction valve below said shock chamber and forming an outlet from the inlet or suction chamber, a

valve plate forming a detachable closure for said pump cylinder and suction valve, said valve plate forming a water passage at the end of the water box into which an end of said cylinder and the suction valve projects, a discharge valve mounted in said valve plate and controlling the discharge of water to the combined water and air chamber, and an air pipe mounted in said valve plate to admit air to said water and air chamber.

9. In a single cylinder pump, a water box having a combined water and air chamber and an inlet or suction chamber, a pump cylinder arranged between said chambers and surrounded by a space which communicates with the upper portion of the suction chamber and constitutes a shock chamber, suction valves in a side and end of said water box respectively communicating with said suction chamber below the pump cylinder, a valve plate forming a closure for the end suction valve and the cylinder, a valve plate forming a closure for the side suction valve, discharge valves mounted in the upper portions of said valve plates and communicating with the combined water and air chamber, the said valve plates providing chambers on the side and end respectively of the water box, the chamber of the end valve plate communicating with one end of the pump cylinder and the chamber of the side valve plate communicating with the other end of said pump cylinder.

In testimony whereof I affix my signature.
AUGUSTINE J. POCOCK.
